JAR LIFTING DEVICE

Thomas J. Novak, St. Paul, Minn.

Application July 8, 1946, Serial No. 681,931

4 Claims. (Cl. 294—31)

1

My invention relates to an improvement in jar lifting device wherein it is desired to provide an apparatus for use in lifting jars into or out of a receptacle or the like.

In the canning of fruit, vegetables, and other materials, it is common practice to place a plurality of jars into a receptacle such as a pressure cooker and to cook the contents of the jars while enclosed therein. It is often difficult to remove the jars after the cooking process in view of the fact that the jars have been heated to a high temperature and in view of the further fact that the jars are often immersed or partially immersed in water at a temperature near the boiling point.

It is the object of the present invention to provide an apparatus which may be used to grip a jar or similar object near the top thereof and to grip the jar so that it may be readily lifted or handled.

A feature of the present invention resides in the provision of a pair of arcuate jaws supported in opposed relation to clamp a jar or the like immediately below the top thereof. These jaws are normally urged into clamping position by resilient means which hold the jaws in jar engaging position. As a result my lifting device will hold a jar firmly unless the jaws are manually spread apart and as a result the danger of dropping the jar due to a momentary release of the clamping pressure is obviated.

A feature of the present invention lies in the provision of a pair of arcuate jaws supported on hingedly mounted arms to move toward or away from each other. Spring means is provided to urge the jaws into clamping position. A pair of pivoted levers are hingedly connected between the jaws by means of which the arms may be forced apart. These levers are normally in angular relationship and means is provided to pivot the levers toward aligned position to spread the arms apart.

A further feature of the present invention lies in the provision of a handle having clamping arms pivotally supported at opposite ends thereof. Lever means is provided connecting the jaws to spread the same apart. An auxiliary handle is supported upon a plunger adjacent the handle of the device. By pressing the auxiliary handle toward the main handle of the device the jaws may be urged apart for manually engaging or disengaging the jar.

These and other objects and novel features of my invention will be more clearly and fully set forth in the following specification and claims.

In the drawings forming a part of my specification:

2

Figure 1 is a perspective view of my jar lifting apparatus in clamping position.

Figure 2 is an elevational view of my jar lifting apparatus with the jaws thereof spread apart in readiness for engaging the neck of a jar.

My jar lifting apparatus A includes the handle member 10 having a pair of clamping arms 11 and 12 pivotally connected thereto. In the form of construction illustrated the upper extremities 10 of the arms 11 and 12 are apertured to receive screws such as 13 and 14. These screws 13 and 14 are accommodated in the apertures of the arms 11 and 12 with sufficient play to permit the free ends of the arms to pivot toward or 15 away from each other a predetermined amount.

The arms 11 and 12 incline toward each other for a distance below the handle 10 and are bent at 15 and 16, respectively, to diverge apart at their lower ends as illustrated at 17 and 19.

20 The lower ends of the arms 11 and 12 are bent inwardly into opposed relation as illustrated at 20 and 21 and the extremities of these arms are bent downwardly at 22 and 23 for attachment with the arcuate jaws 24 and 25. The jaws 24 and 25 are riveted or otherwise attached near their mid-point to the arm extremities 22 and 23 so that the jaws are supported in opposed relation.

25 A loop 26 is mounted on the inner surface of the arm 11 near the point of bend 15 to receive the hook shaped end 27 of a lever 29. A similar loop 30 is provided on the inner surface of the arm 12 near the bend 16 to accommodate the curved hook shaped end 31 of a lever 32. The levers 29 and 32 are pivoted by a common pivot 33 to a plunger 34 which extends through an aperture 35 near the center of the handle 10. An auxiliary handle 36 is secured to the upper extremity of the plunger 34 and this auxiliary handle is preferably either held from rotation relative to the plunger or is circular in outline. In the form of construction illustrated, a pin 37 is supported in a groove 39 in the lower extremity of the auxiliary handle 36 and this pin 40 extends through the plunger 34 to hold the handle from rotation.

30 A spring 40 connects the free ends of the levers 29 and 32, one end of the spring 40 extending through an aperture 41 in the hook shaped end 27 of the lever 29 and the other end of the spring 40 extending through an aperture 42 in the hook shaped end 31 of the lever 32. As a result the arms 11 and 12 are normally urged toward 35 clamping position.

35 The operation of my apparatus is believed obvious from the foregoing description. The jaws 24 and 25 are normally urged together by

the spring 40 so that the apparatus appears as best illustrated in Figure 1 of the drawings. When it is desired to engage the top of a jar or the like, the apparatus A is grasped so that the fingers of a hand extend beneath the handle 10 and the auxiliary handle 36 is positioned in the palm of the hand. By applying a squeezing pressure hand the auxiliary handle 36 is urged downwardly toward the handle 10. The hook shaped ends 27 and 31 of the levers 29 and 32 pivot within the loops 26 and 30 so as to pivot the levers 29 and 32 toward alignment. This action spreads the lower ends of the arms 11 and 12 apart, thus spreading apart the jaws 24 and 25.

While the apparatus is in the spread position illustrated in Figure 2 of the drawings the apparatus may be inserted over the top of a jar so that the jaws 24 and 25 are at the level of the neck 43 of the jar B. The squeezing pressure on the auxiliary handle 36 is then released so that the spring 40 draws the arms 11 and 12 together, thus clamping the jaws 24 and 25 about the neck 43 of the jar. The jar may then be lifted or handled in any desired manner, the tension of the spring 40 holding the jaws thereof clamped about the neck of the jar. The tool is released from the jar by merely urging the auxiliary handle 36 toward the handle 10 so as to spread the jaws into the position shown in Figure 2. When the jaws are released from the neck 43, the apparatus may be removed from the jar.

My tool is particularly useful in lifting or handling headed jars and for lifting jars into and out of liquid which would otherwise injure the hands. My apparatus has the advantage of remaining in place clamped upon the neck of a jar until manually removed, thus obviating any chance of accidental disengagement.

In accordance with the patent statutes, I have described the principles of construction and operation of my jar lifting device, and while I have endeavored to set forth the best embodiment thereof, I desire to have it understood that obvious changes may be made within the scope of the following claims without departing from the spirit of my invention.

I claim:

1. A jar lifting apparatus including a handle, a pair of arms pivotally connected thereto adjacent opposite ends thereof, jar engaging jaws supported by the free ends of said arms, a pair of opposed loops on said arms intermediate the ends thereof, a pair of links pivotally connected together and having hook shaped ends engageable through said loops on said arms, and resilient means connecting the ends of said links to urge said jaws together.

2. A jar lifting device comprising a handle, a pair of arms pivotally connected to said handle

adjacent opposite ends thereof, jar engaging jaws supported adjacent the free ends of said arms, a pair of opposed loops on the opposing surfaces of said arms, a pair of links pivotally connected together to form a knee joint, hook shaped ends on said links extending through said opposed loops, resilient means connecting the hook shaped ends of said links, and plunger means slidably supported by said handle and secured to said links at said knee joint.

3. A jar lifting device comprising a handle, a pair of arms pivotally connected to said handle adjacent opposite ends thereof, said arms being bent to incline toward each other to a point intermediate the ends of said arms, said arms diverging apart toward their free ends, a pair of opposed inwardly extending ends on said arms, a pair of jar engaging jaws supported by said inwardly extending ends, a pair of links pivotally connected together, means pivotally connecting each link to a respective arm adjacent the said point of bend of said arms intermediate the ends thereof, plunger for pivoting said links, said plunger extending through said handle, and a second handle on said plunger spaced from said first named handle, both of said handles being spaced properly to allow them to be simultaneously engaged in the hand.

4. A jar lifting device including a transversely extending handle, a pair of grooves in opposite ends of said handle, a pair of arms supported in said grooves, substantially aligned means extending through said arms and into said handle and loosely connecting said arms to said handle, said arms being supported from pivotal movement about the axis of the handle by said grooves, a pair of links pivotally connected together, each of said links being pivotally connected to a respective arm, plunger means extending through said handle and pivotally connected to said links at the common pivot therebetween, jaws on the free ends of said arms, and resilient means urging said jaws together.
